CARBON RESISTANCE

Application filed January 27, 1927, Serial No. 164,115, and in Germany February 10, 1926.

This invention relates to resistances composed of discs of carbon.

In regulating the voltage of electric lighting sets for railway vehicles, it is usual in 5 many cases to employ a variable resistance composed of a column of carbon discs, which is switched in front of the net-work, and which cuts down the voltage to such degree that the correct number of volts remain for 10 the lamps. This column is made to assume different degrees of resistance by means of varying pressure, and the same is required to devour the excess generator voltage (which depends upon the accumulator 15 charging voltage) beyond the nominal voltage of the lamps.

In this manner the column of carbon discs is frequently required to convert quite considerable amounts of energy into heat, and 20 in such cases it is necessary to artificially increase the surface area in order to avoid excess temperature.

It has hitherto been usual, in the case of 25 given dimensions of the disc area, to perform this increase by making the discs thicker than is absolutely necessary for the required strength. Thus, with equal resistance and loss of watts, the column was increased in length with corresponding increase 30 in the cooling area. In practice the resistance of the column is determined only by the number of and the pressure applied to the contacting faces of the discs, and not by the distance which the current is required 35 to traverse in the carbon.

A difficulty arising in connection with resistances of this type resides in the disturbing effect occasioned by the expansion of the column under heat.

40 In passing over from the lowest to the greatest pressure on the column, the latter varies in length by a certain amount. Within this compression distance the reaction force of the column naturally varies to a 45 considerable degree, and assumes an extremely high value when the discs are pressed very closely together.

With every length of column the reaction force within the compression distance must 50 be made to balance with two other forces,

viz., the force of a spring, which tends to compress the column, and with the pull of a magnet, which is excited by the voltage to be regulated, and which again relieves the column to a certain extent.

55

Towards the end of the stroke where the discs are pressed together, every one-tenth millimetre additional compression causes a very rapid increase in the reaction force.

In accordance with exactly the same law, 60 the pressure exerted by the mechanism on the column must also increase with this displacement if a state of equilibrium between the three forces referred to is to exist in every position of the mechanism.

65

If, on account of excessive heating, the column is somewhat extended in length, the mechanism applying the pressure will also slightly move, and therefore, in accordance with the law referred to, vary its pressure on 70 the column.

Since the reaction force of the column in the case of the increased length occasioned by expansion under heat is exactly the same as in connection with the shorter length in 75 cold state, but the pressure applied by the mechanism has been varied by the displacement, a disturbance has been caused in the state of equilibrium which requires to be again readjusted by variation in the magnetic force, i. e., by variation in the exciting voltage. This is equivalent to a corresponding error in the voltage regulation. It is obvious that this error will be all the greater the thicker the carbon discs, i. e., the longer the 80 column with the same number of discs and accordingly the more the same expands under heat.

85

The present invention covers a method of arranging resistances composed of carbon 85 discs, in which with equal surface area of the column the error in the voltage regulation caused by expansion under heat is considerably less than in the case of the hitherto known arrangements.

95

The essence of the invention consists in producing in the case of a carbon column with given cross-sectional exterior dimensions the desired increase in the surface area, not by making the discs thicker, but by adding to 100

the original column one or more additional columns with discs of like thickness and switching the same in parallel with the original column.

5 The following result is then obtained:

Let it be assumed that the density of current and the maximum pressure per square centimetre is of a given value, and not to be varied. The action of switching in parallel, 10 say, two equal columns occasions with the same density of current a halving of the cross-section of the column. If the discs, for example, are annular in form, the halving of the cross-section may be performed for instance by increasing the inner diameter, or 15 in the case of imperforate discs by providing incisions or scallops, or by varying the cross-sectional form, it being quite understood, of course, that the cooling area should at least 20 not be diminished.

By halving the cross-section of the column it is necessary, for attaining a like specific pressure, to halve the total pressure applied. Thus the mechanism is also required to exert 25 merely half the pressure, and consequently the disturbing effect of the expansion of the column on the compensation of the forces will also be halved.

In reality, however, the error is reduced to 30 less than the half. If the compression distance of a column composed of twice the number of discs of half the thickness were also twice as great as the compression distance of a column composed of half the number of discs of twice the thickness, the transmission stroke of the mechanism on the carbon column in the case of the thin discs would be twice as great as in the case of the thick discs, and the amount of work required to be 35 performed by the mechanism (half the force times the doubled distance) would remain the same. In this case the disturbing influence of the heat would be exactly half that in the case of the thick discs, since the expansion distance of the column in comparison with the compression distance is now only 40 half as great.

However, the compression distance of a column composed of a greater number of 45 thinner discs is by no means greater in proportion to the number of discs than that of a column of equal length having thicker discs, so that on account of the favorable transmission of the mechanism the reaction of a variation in the reaction force on the equilibrium of the magnet is again reduced.

In the drawing

Fig. 1 shows a form of embodiment of the invention.

50 Figs. 2 and 3 showing an additional detail.

In Fig. 1 the carbon discs of the column are designated A, and are, for example, of annular form. B represents three metal rings supplying current, of which the one is situated 55 in the centre and the other two each at

the two ends of the column. C and D are the leads through which the current is supplied, and are so attached that the upper and the lower halves of the column are connected in parallel.

70 In lieu of the columns switched in parallel being placed axially to each other, the same might also be arranged side by side. This arrangement, however, causes complications in the transmission mechanism, and also requires an unnecessary amount of space. Moreover, inexactitudes are noticeable in the mechanism if the movements occur over a small distance and the force is relatively 75 strong.

80 Certain advantages are offered by vertical disposal of the resistance column. This position, however, means that the lower sections of the column are required to bear the weight of those above, and are consequently never entirely relieved, and they do not increase their resistance when the column is 85 fully relieved to the same extent as the top-most section.

86 The invention also relates to a device which overcomes this drawback. The same consists in counterbalancing in the case of each section of the column, with exception of the lowest one, the pressure on the base by means of small counterweights. The appertaining 90 Figs. 2 and 3, forming elevation and plan, show a form of embodiment given by way of example. As in Fig. 1, A designates the discs of carbon, and B metal rings supplying the current. As opposed to Fig. 1, however, two 95 metal rings are provided at the centre of the column, of which the upper one possesses three outwardly projecting lugs E. Each of these is supported by the end F of a two-armed lever G, which is furnished at the 100 other end with a small weight H. The lever G is supported at the centre by a knife-edge J.

105 The weights H are of such weight as to practically entirely counterbalance the pressure between the two metal rings in the centre. In order upon jolts to prevent a break in the current by the two sections of the column opening apart, the lower ring is inserted between, which is electrically connected with the upper ring, and on account of its weight always remains resting on the lower section of the column.

110 Due to the weights H the lower half of the column, when the load is entirely removed from the same, is also fully relieved.

115 In view of the foregoing, it will be clear that any suitable means may be employed to constitute a transmission mechanism for applying to the column of carbon disks the intended pressure to suit the conditions of practical use and merely by way of illustration of a possible form of mechanism for applying pressure to the carbon pile and relieving the latter from pressure, I have shown in Figure 2 diagrammatically a lever 11 pivoted as at 120 125 130

and provided with a suitable member 12, secured thereto as at 13, for engagement with the upper end of the column A of carbon disks. A spring 14 may serve to swing the lever 10 about its pivot 11 so as to cause the carbon pile to be compressed, and a magnet or solenoid 15 may act in opposition to the spring 14 and is adapted to respond to the electrical conditions in the circuit to be regulated and thus to control the transmission of force or pressure to the carbon pile.

It will thus be seen that there has been provided in this invention a carbon resistance in which the several objects hereinbefore noted, as well as many thoroughly practical advantages, are successfully achieved. It will also be noted that the apparatus is well adapted to meet the varying conditions of practical use.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

What I claim as new and desire to secure by Letters Patent is:

- 30 1. In apparatus of the character described, in combination, a carbon pile extending substantially vertically, means for varying the pressure on said pile thereby to vary its resistance, a counter-weight of substantially the same weight as that of an upper section of said pile, and means connecting said counter-weight to the lower portion of said upper section of said pile to substantially balance the weight of said upper portion.
- 40 2. In apparatus of the character described, in combination, a carbon pile extending substantially vertically, means for varying the pressure on said pile thereby to vary its resistance, means for sectionalizing said pile comprising conductive members, one at the bottom of each section and one at the top of each section, means for connecting said sections in parallel and comprising conductors connected to said conductive members, and means acting through the conductive member at the bottom of one section and exerting an upward force sufficient to prevent the weight of said one section from substantially affecting the resistance of a section underneath said one section, the members of said pile being apertured and said conductive members being substantially of plate-like form and apertured, all of said apertured members being related so that the apertures therein are in inter-communication to form an open-ended passage.

In testimony whereof I have affixed my signature.

HUGO GROB.
